David Henderson Houston

UNITED STATES PATENT OFFICE.

DAVID HENDERSON HOUSTON, OF HUNTER, NORTH DAKOTA.

PHOTOGRAPHIC-ROLL HOLDER.

SPECIFICATION forming part of Letters Patent No. 694,930, dated March 4, 1902.

Application filed September 21, 1901. Serial No. 76,114. (No model.)

To all whom it may concern:

Be it known that I, DAVID HENDERSON HOUSTON, a citizen of the United States, residing at Hunter, in the county of Cass and State of North Dakota, have invented certain new and useful Improvements in Daylight-Loading Photographic-Roll Holders; and I do hereby declare the following to be a full, clear, and exact description of the invention, such as will enable others skilled in the art to which it appertains to make and use the same.

My invention relates to an improved roll-holder for use in photographic cameras, in which roll-holder can be used cartridges of sensitized film having a light-tight wrapper.

One object of my invention is to provide an improved roll-holder which is made to separate from the camera and permit the use of plate-holders in the same camera, so that a roll-holder and plate-holder can be used interchangeably in the same camera.

Another object of my invention is to provide a roll-holder having no film-support board, so as to better allow the sensitized film to lie flat between the guides, and the sight-aperture usually carried in and through said film-support board I carry in a novel manner in the rear of a pendent walled sight-passage.

Another object of my invention is to provide a roll-holder having only one compartment for holding the spools of sensitized film and exposing the film to rays of light passed through a lens, in which roll-holder only one sliding door in the casing is necessary, which sliding door is the usual sliding door generally used in the front of all roll-holders and plate-holders.

In my invention my roll-holder has an opening at the front of the roll-holder in the place usually occupied by the film-support board, and thus my roll-holder can be made without any slides, doors, or any opening in the casing for obtaining access to the interior of the roll-holder other than the usual front slide, and the roll-holder thus is accessible for the introduction of supply-spool and reel-spool through the front slide of the casing and through the aperture caused by omitting the film-support board, which support-board is not a necessary element in roll-holders.

My roll-holder has one compartment for

holding the rolls of sensitized film and a walled sight-passage located in the top of the roll-holder casing, which sight-passage leads to 55 one or more sight-apertures in the front of the walled sight-passage, which sight-apertures are near to the rear side of the wrapper of the sensitized film, and through which sight-apertures can be observed numbers, letters, or indicia denoting the position of the sensitized film in the roll-holder.

My invention consists of a photographic-roll holder suitable for using cartridge-rolls of sensitized film, the novel features of which 65 are pointed out in the claims.

In the drawings similar characters of reference denote similar parts.

Figure 1 represents a perspective view of my roll-holder taken from the rear. Fig. 2 70 represents a perspective view of the roll-holder taken from the front and showing the interior of the roll-holder. Fig. 3 represents a central perpendicular sectional view taken through the center of the supply-spool and 75 the reel-spool. Fig. 4 represents a central perpendicular cross-sectional view through the center of the sight-aperture of the roll-holder. Fig. 5 represents a sectional plan view of the roll-holder, taken on the line X X of 80 Fig. 2. Fig. 6 represents a front view of the roll-holder. Fig. 7 represents a modified form of the roll-holder.

A designates the casing; B, the sight-passage; C, the walls of the sight-passage; C', the bottom of the sight-passage; E, the sight-apertures; F, the reel-spool; F', the supply-spool; G, the guide-rollers; H, the slot for the front slide; J, the front slide; K, the lower pivot for the supply-spool; K', the upper 90 pivot for the supply-spool; L, the lower pivot for the reel-spool; L', the reel-winding device; K'', the screw-head of the pivot for the supply-spool; N, the winding-key; R, springs supporting the lower pivots for the supply 95 and reel spools; T, the upper film-edge guide; T', the lower film-edge guide; V, the sensitized film; V', the wrapper of the sensitized film.

To operate the roll-holder, withdraw the 100 front slide and insert a reel-spool through the front opening and place the top of the reel-spool into connection with the reel-winding device. Then press down the lower reel cen-

tering and supporting device and the center pivot can be entered into the lower end of the reel-spool and the reel-spool be in place. Next insert a cartridge-spool of sensitized film in the same manner and pass the end of the wrapper of the sensitized film around the rounded guides and pass the said end of the wrapper along the front of the roll-holder and outside of the film-guides. Then pass the end 10 of the wrapper rearward and around the rounded guide and attach the end of the wrapper to the reel in the usual manner. Then turn the reel forward enough to take up the slack of the wrapper and insert the 15 edges of the wrapper between the outer and inner guides for the edge of the film and tighten the wrapper by turning the reel. Next replace the front slide of the roll-holder casing and turn the reel forward until the 20 first number, letter, or indicia on the wrapper of the film comes opposite to the sight-aperture in the roll-holder, and thus prepared the roll-holder is ready to be inserted in a camera and used in the usual manner.

25 I claim—

1. In a photographic-roll holder the combination of a casing having a front opening, a slide in said front opening, the casing having a walled sight-passage through the top of the 30 casing, said walled sight-passage leading to a sight-aperture in the front of said walled sight-passage, film-edge guides at the interior top and bottom of the casing, rounded guides for the sensitized film positioned in 35 line with the film-edge guides, said rounded guides placed at the sides of the space between the film-edge guides, spool and reel centering devices in the casing, and a reel-winding device adapted to connect with and 40 wind the reel.

2. In a photographic-roll holder the combination of a casing having one compartment for holding the rolls of sensitized film and exposing the film to rays of light passed through 45 a lens, said casing having a front opening, a slide in said front opening, said casing constructed with only one outside opening for introducing spools of sensitized film, which opening is closable by the said slide, said casing having in its top a walled sight-passage having a front wall, said front wall having a sight-aperture, film-edge guides at the interior top and bottom of the roll-holder casing, said film-edge guides positioned in line between 50 the rounded guides for the film, spool and reel centering devices in the casing, and a reel-winding device adapted to connect with and wind the reel.

3. In a photographic-roll holder the combination of a casing having one compartment for holding the rolls of sensitized film and exposing the film to rays of light passed through a lens, said casing having a front opening, a slide in the said front opening, said casing 60 having in its top a sight-aperture, film-edge guides at the interior top and bottom of the roll-holder casing, said film-edge guides posi-

tioned in line between rounded guides for the film, said rounded guides positioned on opposite sides of the space between the said 70 film-edge guides, spool and reel centering devices in the casing, and a reel-winding device adapted to connect with and wind the reel.

4. In a photographic-roll holder the combination of a casing having a front opening, a slide in said front opening, the casing having a walled sight-passage through the top and back of the casing, said walled sight-passage leading to a sight-aperture in the front of said 80 walled sight-passage, film-edge guides at the interior top and bottom of the casing, rounded guides for the sensitized film positioned in line with the film-edge guides, said rounded guides placed at opposite sides of the space 85 between the film-edge guides, spool and reel centering devices in the casing, and a reel-winding device adapted to connect with and wind the reel.

5. In a photographic-roll holder the combination of a casing having a front opening, a slide in said front opening, the casing having a walled sight-passage through the top and back of the casing, said walled sight-passage leading to a sight-aperture in the front of the 95 said walled sight-passage, film-edge guides at the interior top and bottom of the casing, rounded guides for the sensitized film positioned in line with the film-edge guides, said rounded guides placed at opposite sides of the space 100 between the film-edge guides, a pivoting device for the supply-spool, a pivoting and winding device for the reel-spool, a spring carrying spool and reel pivots positioned at the opposite side from the reel-winding device, and the roll-holder casing constructed to open and allow of access to the interior of 105 the roll-holder.

6. In a photographic-roll holder the combination of a casing having one compartment 110 for holding the rolls of sensitized film and exposing the film to rays of light passed through a lens, said casing having a front opening, a slide in said front opening, the casing having a walled sight-passage through the top and 115 back of the casing, said walled sight-passage leading to a sight-aperture in the front of said walled sight-passage, film-edge guides at the interior top and bottom of the casing, rounded guides for the sensitized film positioned in line with the film-edge guides, said 120 rounded guides placed at opposite sides of the space between the film-edge guides, a pivoting device for the supply-spool, a pivoting and winding device for the reel-spool, and a 125 spring carrying spool and reel pivots positioned at the opposite side from the reel-winding device.

In testimony whereof I affix my signature in presence of two witnesses.

DAVID HENDERSON HOUSTON.
